UNITED STATES PATENT OFFICE.

JAMES B. BAILEY, OF NEW YORK, N. Y.

CLOTHES-PIN OR GARMENT-HANGER.

1,284,556.

Specification of Letters Patent. Patented Nov. 12, 1918.

Application filed July 13, 1917. Serial No. 180,430.

To all whom it may concern:

Be it known that I, JAMES B. BAILEY, a citizen of the United States, residing at New York city, in the county of New York and 5 State of New York, have invented new and useful Improvements in Clothes-Pins or Garment-Hangers, of which the following is a specification.

This invention relates to improvements in 10 clothes pins for garment hangers and particularly to a device of this character having separable portions maintained in connection by a spring element from which the clamping action of the device is obtained. In such 15 garment hangers as commonly constructed it is found that in operation the jaws have a tendency toward relative longitudinal and swinging movement rendering the use of the device inconvenient and interfering with the 20 security of the hold obtained. It is therefore the purpose of the present invention to obviate this difficulty by the provision of integrally formed portions of the jaw bars adapted for mutual engagement to form a 25 tongue and groove joint whereby rocking movement of the jaws will be freely permitted and displacement in every direction except laterally will be prevented. It is further intended to so arrange the spring of 30 the device as to prevent such lateral displacement when assembled.

To effect these ends and such others as will hereafter appear I have embodied the invention in the preferred form described in the 35 specification below, delineated in the drawings and having the novel features more broadly set forth in the claim.

In the drawings:

Figure 1 is a side view of the device, 40 Fig. 2 is a longitudinal section illustrating more fully the tongue and groove joint, Fig. 3 is a plan view showing the inner or coincident faces of the jaws.

The hanger designated in the drawings in 45 entirely by the numeral 1 has the usual jaw bars 2 and 3 which are each preferably formed of a single piece of wood. The bar 3 is formed in the inner surface intermediately of the ends with a transverse channel 4 50 which may have a straight side 5 toward the jaw 6 of the bar and which has the upper portion of the other side overlying the channel to form a lip 7 whereby the opening of the channel 4 is restricted in size. From the

lip 7 toward the handle end of the hanger or 55 that end remote from the jaws 6 the inner surface of the bar 3 is preferably beveled as shown in the drawings to permit movement of the jaw bars through a wider angle. The other bar 2 is provided on the inner face intermediate of the ends with a transverse tongue 8 for engagement within the channel 4, and suitably under-cut or formed with a groove 9 in one side for receiving the lip 7. The other side of the tongue 8 is preferably 60 rounded outwardly from the base to permit free rocking movement of the jaws and the tongue 8 is of such width that the rounded side will engage against the straight side 5 of the channel to retain the lip 7 in the 65 groove 9. It will be seen that in assembling the pin the tongue will be entered in the groove by lateral movement and to prevent subsequent lateral displacement the clamp 70 spring 10 for the bar 6 has a helical coil 11 disposed on each side of the bar and connected by a straight portion 12 lying between the jaws which may be channeled for this purpose when desired. The end of each 75 spring coil extends toward the jaw of a respective bar and is bent laterally to engage in a groove formed transversely in the outer surface of the particular jaw bar. For increasing the holding power of the hanger each jaw 6 is formed in the inner surface 80 with a plurality of parallel transverse grooves 13 coinciding in the closed position of the jaws.

When desired the bar 3 may be cut away toward the jaw 6 to form a shoulder 14 85 adapted for engagement with a similar shoulder 15 and the other bar 2 formed with a shoulder 16 abutting against the shoulder 15 to further prevent longitudinal movement of the bars. The handle end of the bar 2 is 90 preferably reduced in thickness as shown toward the tongue 8 to increase the angularity of opening of the jaws and permit unrestricted movement of the lip 7.

The herein described form of the invention while considered preferable constitutes 100 but one of many comprised within the scope of the invention and the right is reserved to all variations and departures therefrom falling within the spirit of the invention as indicated by the latitude of the claim.

What I claim is:

A clothes pin comprising a pair of bars

each terminating at its forward end in a jaw, one of said bars being provided at its center with a transverse groove, having a forward overhanging edge constituting a tongue, the 5 other bar being provided with a rearwardly extending tongue engaging in said groove and having a groove receiving said first named tongue, said interfitting tongues and grooves providing a pivot point for said bars, a projection on one bar extending into 10 a recess in the other bar for preventing relative longitudinal movement of the bars and a spring for urging said bars together.

In testimony whereof I affix my signature.

JAMES B. BAILEY.
